UNITED STATES PATENT OFFICE

1,984,800

ELECTROMAGNETIC SPEAKER

Jack Jensen, Oakland, Calif.

Application April 25, 1929, Serial No. 357,936

6 Claims. (Cl. 179—115.5)

This invention relates to loud speakers and especially relates to that class commonly called electromagnetic speakers that are used in connection with radios.

5 It is one of the objects of the present invention to concentrate the magnetic field by providing a gap of varying length between the pole-pieces. It is another object of the invention to provide an improved and exceptional simple constructed 10 housing, for the cone, that is made out of one piece of sheet metal and is formed in one pressing operation.

The invention further consists in the particular combination, form of construction and 15 association of the different elements, such as described in the following specification and possesses other objects and features of advantage, some of which, with the foregoing, will be made manifest in the preferred form of the invention 20 which is illustrated in the drawing accompanying and forming part of the specification.

It is to be understood that it is not intended to limit the invention to the embodiment shown by said drawing and description, as variations 25 may be adapted within the scope of the invention as set forth in the claims.

In the accompanying drawing:

Figure 1 is a central longitudinal sectional view of one type of speaker involving the invention.

Figure 2 is a partial sectional and side elevational view of one stud used in the invention.

Figure 3 is a perspective view of the cone and sound coil tube support.

35 Figure 4 is a sectional view taken on line A—A of Figure 1, looking in the direction of the arrows.

Figure 5 is a perspective view of a cut-out upper polepiece which may be mounted on the central pole to form a gap of varying length.

Referring in detail to the different parts wherein like reference characters denote corresponding parts throughout the several views, numerals 9 and 10 designate two flat pole-pieces 45 that may be made out of any suitable metal, but are preferably made of standard square cold rolled steel and are held together by a plurality of bolts 12 as illustrated in Figures 1 and 4. The said bolts are made of a size sufficient to properly carry the magnetic flux and are preferably constructed as shown in Figure 2, having a reduced threaded portion 12a on the front end and an internally threaded hole 12b in the rear end. The front plate 9 is provided with threaded 50 holes into which the said bolts are screwed and

are locked thereto by means of lock nuts 15. The rear plate 10 is fastened to the bolts by a plurality of cap screws or bolts 16 that are projected through the plate 10 and threaded into the tapped holes 12b of the bolts 12. A central pole 17 preferably made of soft cold rolled steel, is formed with a reduced portion 17a, and the said portion 17a is mounted in a hole provided in the center of the plate 10 being peened therein as shown in Figure 1. A field coil 18 is provided on the central pole 17 as illustrated.

It is desirable to provide an air gap of varying length between the pole-pieces by reducing the pole-piece surfaces in such a manner as to increase the magnetic density in the narrow portions of the gap and thus increase the efficiency of the speaker. In Figures 1 and 4 there is illustrated a certain shape of opening 9e in the front plate 19, but it is to be definitely understood that any suitable shape may be used. A shaped upper 20 pole piece 20, formed with spaces 20a preferably as illustrated in Figures 3 and 8, is provided, and is mounted on the front end of the center pole-piece 17, and is fastened thereon with a fillister head screw 21 as shown in Figure 1. The upper 25 pole piece 20 is preferably arranged as shown with the spaces 20a, respectively, coinciding with the spaces in the opening in the plate 9. The spaces 20a may be provided directly in the central pole 17 if desired. This construction enables the piece 20 to be provided in different sizes, and also, simplifies machine work.

A cone 22, made out of paper or fiber or any suitable material, such as used in standard practice, is provided, and is mounted within an especially constructed cone housing 23 that is fastened on the plate 9 by the studs 12 and the nuts 15 as shown in Figure 1. The cone housing is preferably made out of one piece of sheet metal and is first blanked out as shown in Figure 6, after which it is bent into the form as shown in Figure 7. The cone 22 is fastened to the housing 23 by means of a circular member 24 that is preferably made out of flexible material, such as leather, and is glued, or otherwise fastened by any suitable means, to both the housing 23 and the cone 22 as shown in Figure 1. At the small end of the cone, a tube 24, that is preferably made out of the same material as the cone, is provided and is glued to the cone and extends into the opening 9e in the front plate 9 and around the member 20 that forms the center upper pole-piece. The inner diameter of the tube 24 is made approximately one thirty-second 50 55

of an inch larger in diameter than the outer diameter of the said member 20 to permit the tube to have longitudinal movement over said member 20 without having contact therewith, or 5 with the front plate 9.

A thin non-magnetic plate 25, hereinafter called the vibrating plate, that is cut out preferably as shown in Figure 5, is mounted on the ends of the studs 12 and is held tightly against 10 the nuts 15 by the nuts 26. A split metal cone shaped washer 27 as shown in Figure 3 is glued to both the cone 22 and the tube 24, and is fastened to the vibrating plate 25. The said cone washer is provided with a circular end portion 27a that is notched as shown in Figure 3, and the said end portion 27a is mounted in a hole 25a in the vibrating plate and the notched ends thereof are bent firmly around the plate and fastened substantially thereto as shown in 15 Figure 1. A copper coil 28, hereinafter called the sound coil is mounted around the cone tube 24 and one end of the sound coil is fastened to the input terminal 27b on the cone washer and the other end of said coil is fastened to the output terminal 27e. Numerals 29 and 30 designate 20 electric conductors that lead from the terminals 27b and 27e to the audio frequency circuit. A copper plate 31 is arranged between the field coil and the sound coil to provide a shield between the two coils to reduce the hum 25 caused by pulsating current. The said copper plate is preferably formed square as shown in Figure 4 and is cut out on the corners to fit closely to the bolts 12 as illustrated.

From the foregoing it will be seen that a magnetic field will be produced in the air gap 9e when direct current is passed through the field coil 18 and when the sound coil 28 is connected to an audio frequency circuit through electric 40 conductors 29 and 30 it will further be seen that modulated audio currents will pass through the sound coil and will produce a magnetic field of their own that will react upon the strong magnetic field in the air gap 9e with a force that is proportional to the current that passes through 45 the sound coil, which will cause said sound coil to vibrate in proportion to the current that passes therethrough, and as said coil is fastened to the cone, the cone will be caused to vibrate in unison with said coil, thus producing sound. It will be noted also that cutting away portions 50 of the pole pieces in no way alters the total magnetic flux but rather concentrates it at the four uncut portions of the gap, therefore the same effective magnetic flux is maintained in the gap while, due to the reduction of the length of the gap, the chance of dirt or other foreign matter 55 entering the limited space between the pole pieces and the sound coil is reduced.

60 A further beneficial result is obtained by this construction, in that eddy currents, with their attendant losses, are reduced due to the fact that

there are no closed circuit low resistance paths in either pole piece closely adjacent the sound coil.

Having thus illustrated a certain form of construction and arrangement of parts pertaining to the invention, it is to be understood that the improvements may be embodied in any electro-magnetic speaker, which, obviously, may be built up in any suitable manner, the present illustration not being utilized as indicating the only 10 form of construction into which the parts may be made; and it is desired to include in this application for Letters Patent of the United States of America, any and all patentable novelty that exists in the invention disclosed and all that 15 comes within the range of the invention as set forth in the claims hereinafter mentioned.

What is claimed is:

1. A sound reproducer comprising a magnetic circuit, an annular air gap in said circuit, a 20 cylindrical sound coil inserted in said air gap, and an actuating means attached to said coil, a portion of said magnetic circuit being removed at said air gap to concentrate the magnetic field with different intensities on different circumferential portions of said cylindrical coil.

2. A sound reproducer comprising a central polepiece, an outer polepiece having an opening surrounding and spaced from the inner polepiece, a circular sound coil positioned within 30 the space between the polepieces, and sound actuating means attached to said sound coil, said polepieces being symmetrically cut away in a plane at right angles to the axis of said coil to cause a concentration of magnetic density on 35 different circumferential portions of said sound coil.

3. A sound reproducer comprising a central polepiece, an outer polepiece having an opening surrounding and spaced from the inner polepiece, a circular sound coil positioned within 40 the space between the polepieces, and sound actuating means attached to said sound coil, said polepieces being shaped to provide an air gap of varying length in a plane at right angles 45 to the axis of said coil.

4. A sound reproducer comprising a magnetic circuit having an annular air gap, a sound coil in said gap, and means for causing the flux density intersecting said coil to differ in different 50 circumferential portions of said coil.

5. A sound reproducer comprising a magnetic circuit having an annular air gap, a sound coil in said gap, and means for concentrating the flux in said air gap upon regularly spaced circumferential portions of said coil.

6. A sound reproducer comprising a magnetic circuit having an annular air gap, a sound coil in said gap, and means for applying a different flux density to various portions of said coil 60 around the circumference thereof.

JACK JENSEN.
